(57) **CLAIM**

The ornamental design for a disposable charcoal chimney, as shown and described.

DESCRIPTION

FIG. 1 is a front perspective view of a disposable charcoal chimney showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof;
FIG. 7 is a bottom plan view thereof; and,
FIG. 8 is a partial cut away view of the bottom side portion thereof taken along line 8-8 in FIG. 5.
